COMBINATION MEAT VENDING AND DISPLAY MACHINE

Anthony John Maddalena, Brooklyn, N. Y.

Application March 8, 1956, Serial No. 40,518

Term of patent 14 years

(Cl. D52—3)

FIG. 1.

FIG. 2.

FIG. 3.

Figure 1 is a front perspective view of a combination meat vending and display machine, showing my new design.

Figure 2 is a fragmentary front perspective view showing one of the meat compartments drawn to an enlarged scale and showing the pivoted access door to the compartment in open position.

Figure 3 is a rear perspective view of the machine depicted in Figure 1, showing rear access doors, through which the machine is loaded and serviced, in the open position.

I claim:

The ornamental design for a combination meat vending and display machine, as shown.
